SIGURD CLAUSEN, OF BROOKLYN, NEW YORK, ASSIGNOR TO INTERNATIONAL CIGAR MACHINERY COMPANY, A CORPORATION OF NEW JERSEY

REROLLING BUNCH FORMER

Application filed January 18, 1932. Serial No. 587,426.

This invention relates to an improvement in cigar making machines and in particular to the bunch rolling mechanism of the same, its main object being to provide improved means for rolling the filler or charge of a cigar bunch back and forth in different positions about its periphery during the early portion of the rolling operation before much of the binder is rolled around the charge, thereby gaining the advantage that the major portion of a one-piece binder, or the second part of a two-piece binder, is left completely undisturbed while the high spots and flat portions in the filler are softened and distributed, the binder as a whole being completely rolled around the charge only after the latter has been rolled and re-rolled a number of times, thereby insuring a soft and perfectly round bunch upon the completion of the rolling operation. With this and other objects not specifically mentioned in view, the invention consists in certain constructions hereinafter fully described and then specifically set forth in the claims.

The bunch rolling in a cigar making machine is performed on a rolling table by a chianti belt which is actuated by a bight forming roller or rolling pin. The binder is laid on the chianti belt near the forward end of the same, which extends across the rolling table when the bight forming roller is in its rearmost or starting position. The filler charge is placed in a loop formed in the rear end of the chinati belt, between the rolling table and the bight forming roller. As the latter moves forward across the rolling table, the charge is first rolled by itself in the chinanti belt and is then rolled into the binder which is held flat on the rolling apron by means of suction provided by a suction fan of the cigar machine.

In the accompanying drawings:

Fig. 1 is an end elevation of the improved cigar bunch rolling mechanism;

Fig. 2 is a side elevation of the same on line 2—2 of Fig. 1;

Fig. 3 is a plan view of the improved bunch rolling mechanism;

Fig. 4 is another plan view in enlarged

scale showing diagrammatically the forward-and-reverse motion of the rolling pin; and

Fig. 5 is a detail side elevation, partly in cross-section, showing the constituent parts of the bunch rolling mechanism.

55

In carrying the invention into effect there is provided a rolling table, a chianti belt, a bight forming roller or rolling pin supported by a slide, and means connected to the slide to advance the bight forming roller across the rolling table, said means being constructed to give the bight forming roller reverse or backward movements during its advance across the table to manipulate the bunch. In the preferred form of construction, said means includes a rock lever connected to the slide, a cam lever connected to said rock lever and provided with a cam roller, and a cam having a cam track in which said cam roller is disposed, the cam track being shaped to cause reverse movements of the bight forming roller during the early portion of its advance across the rolling table to manipulate the bunch before the binder is completely rolled about the same. These 75 various means and parts may be widely varied in construction within the scope of the claims for the particular device selected to illustrate the invention is but one of many possible concrete embodiments of the same. The 80 invention, therefore, is not to be restricted to the specific construction shown and described.

Referring to the drawings, the improved cigar bunch rolling mechanism consists of a 85 rolling table 10 supported by a pedestal 11 which is mounted on the main frame 12 of the cigar machine. One end of the chianti belt 13 is fastened to the rolling table 10 by means of a bar 14 while the other end is clamped 90 to a tension roller 15 of well known construction equipped with tightener chain 16 which is operated from the main drive of the cigar machine. The chinanti belt 13 rests on a bight forming roller or rolling pin 17 the movement of which actuates the same. Bight forming roller 17 is mounted in a bracket 18 fastened to a slide 19 supported by guide ways 20 mounted on pedestal 11. Slide 19 receives reciprocating motion from a rock 100

lever 21 connected to slide 19 by means of a link 22. Lever 21 is pivoted on shaft 23 and operated through a connecting rod 24 by a lever 25 mounted on a shaft 26 on which is mounted a cam lever 27 having a cam roller 28 engaging with a cam track 29 of cam 30 on shaft 31, driven from the main drive of the cigar machine.

The binder B is laid on the chianti belt 13 which extends across the rolling table 10 when the rolling pin 17 is in its rearmost or starting position, Figs. 4 and 5. The binder B is held flat on the chianti belt 13 by means of suction provided by a suction fan 32 mounted on frame 12 and operated from the main drive of the machine. The suction passes through a pipe 33 into channels 34, Figs. 2 and 5, of the rolling table 10, and acts on the binder B through holes 35, Fig. 3, with which apron 13 is provided. The charge or filler F is placed by a transfer arm, not shown, into a bight or loop 13a formed by the descent of this arm in the rolling apron 13, between the rolling table 10 and the rolling pin 17 which at that time is in its starting position, as shown in Fig. 5. When the rolling pin 17 moves toward the rolling table 10, the loop 13a closes and tightens around the filler F, see position A in Fig. 5, and on its further forward motion across the rolling table 10, the binder B rolls around the filler F and thereby forms a cigar bunch C which is delivered to a transfer finger 36 at the forward end of table 10. Rolling pin 17 is guided by a roller 37 engaging with a track 38 fastened to rolling table 10.

In making cigar bunches by machine, it has been the experience that there will be high spots and flat portions, particularly at the portions of the filler which were cut to form the charge, which often results in unsatisfactory bunches. To overcome this difficulty, the rolling pin 17 in the present invention is given a number of reverse movements during the early portion of the rolling operation before the filler has entered very far into the binder. These reverse movements of the pin 17 are effected by equipping the cam track 29 with a number of depressions thereby imparting to the cam lever 27 a rocking motion. Thus, when roller 28 travels from lever-position L to L1 in Fig. 2, rolling pin 17 will move forward from R to R1 in Fig. 4. When the roller 28 then travels from L1 to L2 at the bottom of the first depression, the pin 17 is caused to move backward from R1 to R2. As the roller 28 travels further to L3 at the top of the second depression, the pin 17 moves forward again to R3, and so on, the positions L4, L5, L6, L7, L8, L9, and L10 of the roller 28 corresponding to the positions R4, R5, R6, R7, R8, R9, and R10, respectively, of the rolling pin 17. After the roller 28 has passed position L10, the pin 17 from point R10 moves

forward only, there being no more bumps in the cam track 29.

It is most important that the re-rolling of the bunch is performed in the early part of the rolling operation and before much, if any, of the binder is rolled about the filler, so that the major portion of the binder is left undisturbed and the high spots and flat portions in the filler are softened and distributed before the binder is completely rolled around the same, as only a bunch rolled in such a manner will be uniformly soft and perfectly round.

What is claimed is:

1. In a bunch rolling mechanism, the combination with a rolling table, of a chianti belt extending over said table and having one of its ends fastened thereto, a tension roller to which the other end of said belt is fastened, a slide, guide ways for said slide, a bight forming roller supported by said slide, and means connected to said slide to advance said bight forming roller across said table, said means being constructed to give the bight forming roller backward movements during its advance across the table to manipulate the bunch.

2. In a bunch rolling mechanism, the combination with a rolling table, of a chianti belt extending over said table and having one of its ends fastened thereto, a tension roller to which the other end of said belt is fastened, a slide, guide ways for said slide, a bight forming roller supported by said slide, and means connected to said slide to advance said bight forming roller across said table, said means being constructed to give the bight forming roller backward movements during its advance across the table to manipulate the bunch, said means including a rock lever connected to said slide, a cam lever connected to said rock lever and having a cam roller mounted thereon, and a cam having a cam track in which said cam roller is disposed, said cam track being shaped to cause reverse movements of the bight forming roller during the early portion of its advance across the rolling table to manipulate the bunch before the binder is completely rolled about the same.

3. In a cigar bunch rolling mechanism, the combination with a rolling table, of a perforated chianti belt extending over said table and having one of its ends fastened to said table, a tension roller to which the other end of said belt is fastened, suction means acting through the perforations of said belt to retain a bunch binder thereon, a slide, guide ways for said slide, a bracket carried by said slide, a bight forming roller arranged to engage the under side of said belt and having one end mounted in said bracket, a guide roller on the other end of said bight forming roller, a guide track arranged to engage said guide roller, and means includ-

ing mechanism connected to said slide to advance said bight forming roller across said table, said means being constructed to give the bight forming roller successive backward movements during its advance across the table to manipulate the bunch.

4. In a bunch rolling mechanism, the combination with a rolling table, of a chianti belt extending over said table, a bight forming roller acting on said belt and means for advancing said bight forming roller to roll a filler charge into a binder on said chianti belt to form a bunch, said means including mechanism for giving to said bight forming roller a series of backward movements during its advance across the table, all of said backward movements being confined to the rolling operation on the first half of the binder whereby the second piece of a two piece binder will not be displaced.

5. In a bunch rolling mechanism, the combination with a rolling table, of a chianti belt extending over said table, a bight forming roller acting on said belt, and means operating said bight forming roller to roll filler into a binder on said chianti belt to form a bunch, said means including mechanism for giving to said bight forming roller a series of backward movements during its advance across the table with each backward movement terminating at a point in advance of the previous backward movement to progressively give maximum manipulation to the filler charge at a series of spaced positions about its periphery.

In testimony whereof, I have signed my name to this specification.

SIGURD CLAUSEN.
